PUMP

Andrew G. Griparis, Joliet, Ill., assignor to Stainless Steel Pump Company, Joliet, Ill., a corporation of Illinois

Application March 13, 1959, Serial No. 54,971

Term of patent 7 years

(Cl. D65—1)

Fig. 2.

Fig. 3.

I claim:

The ornamental design for a pump, as shown and described.
